UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

CAP FOR LAMP-SOCKETS AND THE LIKE.

1,135,193.

Specification of Letters Patent. Patented Apr. 13, 1915.

Application filed April 8, 1912. Serial No. 689,288.

To all whom it may concern:

Be it known that I, CHARLES J. KLEIN, a citizen of the United States, residing at Milwaukee, in the county of Milwaukee and State of Wisconsin, have invented new and useful Improvements in Caps for Lamp-Sockets and the like, of which the following is a full, clear, concise, and exact description, reference being had to the accompanying drawing, forming a part of this specification.

My invention relates to improvements in caps for lamp sockets, pendant switches and devices of a similar character.

It is one of the objects of my invention to provide a cap which will not require the use of a separate insulating lining therefor.

A further object is to provide a cap of solid insulation with a metallic shell engaging portion.

A further object is to provide a cap of solid insulation having a metallic fixture engaging portion.

A further object is to provide a cap having a metallic shell engaging portion and a metallic fixture engaging portion insulated from one another.

A still further object is to provide a cap of the character described having exteriorly the finished appearance of an ordinary metallic cap.

Other objects and advantages will be hereinafter set forth.

For the purpose of disclosing the nature and characteristic features of my invention, I shall describe the embodiments thereof illustrated in the accompanying drawing. It should be understood however, that my invention is not limited to the specific embodiments thereof selected for the purpose of illustration.

In the accompanying drawings:—Figure 1 is a vertical sectional view through one form of cap. Fig. 2 is a bottom plan view of Fig. 1, and Fig. 3 is a vertical sectional view through a modified form of cap.

The cap shown in Fig. 1 is particularly suitable for use in lamp sockets but might be used in other devices. It includes a dome shaped solid insulating member 1 to which are secured metallic parts as will be later described. The member 1 forms the body of the cap and is accordingly preferably of a substantial character. It may be formed of any suitable material and in any desired

manner. In practice, however, I prefer to form this member of porcelain or some other molded material. The member 1 is provided with a suitable central opening 2 for the passage of wires therethrough.

At its lower end the member 1 is provided with an angularly disposed annular metallic rim 3 which in practice may be secured thereto in any desired manner. I prefer, however, to provide the rim 3 with a perpendicularly disposed annular flange 4 and to mold said flange in the insulating body during the formation of the latter. This produces a unitary, strong and durable structure. If desired the flange 4 may be provided with a roughened or irregular surface or provided with a series of perforations (shown in dotted lines) to augment the grip of the molded material thereon.

The flange 3 supports or carries a shell engaging member 5. The member 5 is of the same construction as that shown in my co-pending application, Serial No. 660,845, filed Nov. 15, 1911, and is secured to the rim 3 in the same manner. Of course in practice the member 5 might be of any other desired form and secured to the rim 3 or directly to the insulating member 1 in any desired manner.

At its top the insulating member 1 is provided with a metallic threaded nipple 6 axially alined with the opening 2. The nipple 6 is provided with a flange 7 shaped to closely fit upon the member 1 and said flange is rigidly secured to said member 1 by rivets 8. The heads of the rivets are preferably countersunk in the insulating member 1 as shown at 9. Of course in practice the nipple might be secured to the member 1 in any other preferred manner. The rivets, however, provide a rigid and serviceable connection between the two. As shown in Fig. 1 the flange 7 of the nipple extends down to a point in close proximity to the other metallic parts described. Accordingly the flange forms in effect a complete covering for the insulating member 1, thereby giving the cap the finished appearance of a solid metallic structure.

The cap thus provided has all of the advantages of the ordinary solid metal caps and further has additional advantages. The insulating member 1 presents an interior insulating surface which obviates the necessity of providing a separate or special insulating

lining. Further it insulates the nipple 6 and flange 7 from the other metallic parts thus insulating the device to which it is attached from the fixture to which it is attached. It thus in effect forms an insulating coupling between the fixture and the device to which it is attached. It is simple and easy to assemble. It is substantial and durable. Still further it may by the use of suitable insulating material be adapted to be bodily immersed in acid to give the desired finish thereto without danger of injuring any of the parts thereof. This obviates the nuisance of having to remove the insulating lining of ordinary caps before subjecting the same to such treatment.

The cap shown in Fig. 3 differs from that shown in Figs. 1 and 2 only in omission of the metallic covering for the insulating member and the provision of an integral insulating nipple 10 for the metallic nipple of the former structure. Such a cap is particularly adapted for use in pendant switches and the like where a threaded nipple is not required. Obviously, however, a metallic threaded nipple might be secured within the insulating nipple 10 if desired, thus adapting the device to the same uses as the cap shown in Figs. 1 and 2.

What I claim as new and desire to secure by Letters Patent is:

1. A cap for lamp sockets and the like comprising a metallic dome member, an insulating lining member secured therein and an annular metallic shell engaging member fixed to said insulating lining member.
2. A cap for lamp sockets and the like comprising a metallic dome member, an insulating lining member secured therein and

a metallic shell engaging member fixed to said insulating lining member, said lining member insulating said metallic dome member from said metallic shell engaging member.

3. A casing cap comprising a body part of insulating material, a metal ring rigidly fixed in the margin of said body part, and a metal shell engaging rim rigidly fixed to said ring, said rim having thereon integral locking shoulders.

4. In combination, a dome member of rigid insulation having an opening for conductors, a metal bushing alined with said opening and rigidly fixed to said member for attaching the same to a suitable support, and a metal rim rigidly and permanently fixed to said member and spaced from said bushing, said rim being adapted to receive a metal shell and said member serving to insulate said rim and the shell received thereby from said bushing and the attached support.

5. In combination, an insulating member, a threaded metal bushing fixed thereto for attachment to a suitable support, and an annular metal rim permanently secured to said member and spaced from said bushing, said rim being adapted to receive a metal shell and said member serving to insulate said rim and the shell received thereby from said bushing and the attached support.

In witness whereof, I have hereunto subscribed my name in the presence of two witnesses.

CHARLES J. KLEIN.
